UNITED STATES PATENT OFFICE.

EMILE C. GUEDON, OF SCHENECTADY, NEW YORK, ASSIGNOR TO GENERAL ELECTRIC COMPANY, A CORPORATION OF NEW YORK.

APPARATUS FOR PRODUCING SOUND.

Application filed July 18, 1927. Serial No 206,408.

My invention relates to apparatus for producing sound and has for its principal object the provision of an improved sound producing apparatus which is simple and rugged in 5 construction and may be readily operated to convert electrical impulses into sound or vice versa.

Various apparatus have been provided in the past for converting electrical or mechanical impulses into sound. Many of these apparatus comprise parts which are moved either in accordance with electrical impulses dependent on sound or in accordance with the contour of a sound record. When the 15 operation of such apparatus involves the use of moving parts, difficulty is frequently encountered due to sound distortion produced by the tendency of these parts to vibrate at frequencies dependent on their individual 20 free vibration periods. In accordance with my invention this difficulty is minimized or altogether avoided by the provision of means comprising an improved movable part which is light in weight and is so mounted that it 25 rotates about an axis near its center of mass.

My invention will be better understood from the following description when considered in connection with the accompanying drawings and its scope will be pointed out in 30 the appended claims.

Referring to the drawings, Fig. 1 illustrates certain details of a sound producing apparatus constructed in accordance with my invention; Figs. 2 to 6 illustrate various constructional features of this apparatus. Figs. 7 to 35 9 illustrate a modification in the armature mounting of the apparatus; Figs. 10 to 12 illustrate a further modification in the armature mounting of the apparatus; and Fig. 40 13 illustrates a modification in the construction of the movable armature of the apparatus.

The sound producing apparatus illustrated by Fig. 1 comprises an electrical device 45 which is clamped to a support 1 by a pair of bolts 2 and is coupled to a conical diaphragm 3 through a driving rod 4. This device comprises a magnet 5 provided with bipartite pole pieces 6 and 7 which are arranged to support and partly enclose a coil 50 8 comprising leads 9 and 10. A movable armature 11 is pivoted within the coil 8 and is connected to the driving rod 4 through a rod 12 and a resilient member 13 attached 55 to one of the pole pieces 7 by means of a

screw 14. As shown more clearly by Fig. 2, the armature 11 is made by folding a sheet of metal so that its opposed edges are slightly spaced from one another, and so that lugs 15 and 16 are formed by punched-out portions of the sheet metal. These lugs are soldered or otherwise fixed to the inner surface of the spool on which the coil 8 is wound and form between the spool and the armature a resilient pivotal connection which is 60 located intermediate the ends of the armature near the rotational axis of the armature and tends to maintain opposite ends of the armature in predetermined positions between the pole pieces 6 and 7. It should be noted 65 that the pole pieces are attached to the magnet 5 by means of screws 16' (see Fig. 3) which preferably extend through slots in the ends of the magnet 5 and are arranged to permit adjustment of the air gap between 70 the pole pieces.

As indicated more clearly in Figs. 4 to 6, the armature 11 is made from a sheet 17 by punching out the ends of the lugs 15 and 16 and folding the sheet into the form shown by 80 Fig. 5. In this form, the armature 11 is inserted in the tubular member 18 which is provided with slots 19 adapted to receive the lugs 15 and 17 and is attached to these lugs by means of solder applied through the slots 85 19, by welding, or in any other suitable manner.

In the operation of the apparatus, electrical impulses from a suitable source are applied to the coil 8 through the leads 9 and 10; the opposite ends of the armature 11 are rocked to and fro in the air gap between the pole pieces 6 and 7; and the diaphragm is caused to vibrate and produce sound dependent on the electrical impulses applied to the 90 coil 8. It will be apparent that the driver rod 4 may be replaced by a stylus holder arranged to maintain a stylus in contact with a sound record in which case the electrical device is utilized to produce electrical impulses dependent on the contour of the groove of such a record and these impulses are supplied to any suitable amplifying or sound producing apparatus.

The armature may be supported in various ways. Fig. 7 shows a resilient bar 20 which is inserted through slots in the side of an armature 21 and is pivoted to the spool of the coil 8 as previously described. It will 105 of course be understood that the member 20 110

must be rigidly attached to the armature 21 and to the spool of the coil.

As shown by Figs. 8 and 9, the resilient member 20 may be attached to a collar 22 which is made of non-magnetic material of high resistivity and is spun over the inner edges of the spool. In this modification of the invention a driver rod 23 has one of its ends fitted into the slot of the armature and is threaded at its free end to permit its attachment either to a diaphragm or to a stylus holder.

The modification illustrated by Figs. 10 to 12 differ from those previously described in that an armature 24 is supported by means of a pair of resilient members 25 which are fixed either to the collar 22 or to the inner surface of the coil 8.

Fig. 13 shows an armature which is made by folding a T-shaped sheet so that the top of the T forms lugs 26 and 27 which are attached either to the inner surface of the spool or to the collar 22 as previously described.

It will be apparent that an armature made by folding a sheet of metal so that its opposite edges are slightly spaced from one another possesses low inertia, is rigid, and is subject to low hysteresis and eddy current losses due to the fact that it is both hollow and slotted. It has been found that when an armature is supported near its center of mass there is little, if any, tendency for it to vibrate at a frequency other than that corresponding to the sound to be transmitted. A further advantage of this construction is that the armature and its pivotal support lugs may be formed as an integral member, thus greatly simplifying the construction of the apparatus.

The embodiments of the invention illustrated and described herein have been selected for the purpose of clearly setting forth the principles involved. It will be apparent, however, that the invention is susceptible of being modified to meet the different con-

ditions encountered in its use and I therefore aim to cover by the appended claims all modifications within the true spirit and scope of my invention.

What I claim as new and desire to secure by Letters Patent of the United States, is—

1. An integral armature member provided with opposed edges spaced from one another to form a slot and with outwardly extending mounting lugs.

2. The combination of means for producing a magnetic field, a coil mounted in said field, a sheet metal armature provided with opposed edges spaced from one another to form a slot and connected to said coil through a resilient connection for varying the path of the flux of said field through said coil, a diaphragm, and means for coupling said armature to said diaphragm.

3. A sound producing apparatus comprising a hollow coil, and an integral armature member provided with opposed edges spaced apart to form a slot and with outwardly extending resilient lugs mechanically connected to the spool of said coil.

4. A sound producing apparatus comprising a hollow coil, and an integral armature member provided with opposed edges spaced apart to form a slot and with outwardly extending resilient lugs mechanically connected to the spool of said coil, a diaphragm, and a driven rod connected between said armature and said diaphragm.

5. A sound producing device comprising a coil, an armature mechanically connected to said coil through a resilient connection, a diaphragm, a resilient member fixed to said coil at one end and to said diaphragm at the other end, means for connecting said armature to said resilient member at a point intermediate said ends, and means arranged to produce a magnetic field within said coil.

In witness whereof, I have hereunto set my hand this 16th day of July, 1927.

EMILE C. GUEDON.
